GEORGE C. CUMMINGS, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,409,362.

Specification of Letters Patent. Patented Mar. 14, 1922.

Application filed May 28, 1918. Serial No. 237,010.

To all whom it may concern:

Be it known that I, GEORGE C. CUMMINGS, a subject of the King of Great Britain, residing at East Orange, in the county of 5 Essex, State of New Jersey, have invented certain new and useful Improvements in Telegraph Systems, of which the following is a full, clear, concise, and exact description.

This invention relates to telegraph systems and more particularly to systems of duplex telegraphy.

The principal object of this invention is to provide an improved organization of apparatus to permit a more nearly exact balancing or neutralizing effect with respect to telegraphic receiving devices and the real and the artificial line circuits of duplex equipments.

In seeking to employ current amplifiers 20 in the reception of telegraphic currents, it has been found that the degree of balance possible with standard or commonly employed duplex equipments is not sufficiently accurate since incipient line variations and 25 slight unbalance of a real line with respect to an artificial line, although not directly capable of appreciably affecting associated receiving devices, may nevertheless become effective through a current amplifier to cause 30 serious difficulty in the working of duplex systems.

In order to remedy this condition and thereby make it possible to secure the obvious advantages in the application of current 35 amplifiers for augmenting the relatively feeble signaling currents as more particularly employed in connection with signaling over submarine cables, composite circuits or long land lines, the present invention contemplates the employment of neutralizing or compensating equipments to be included with a regular duplex equipment in such a manner that associated telegraphing receiving devices may be shielded or protected from extraneous 45 currents present through lack of nicety of adjustments in the balancing of duplex circuits.

This invention is illustrated diagrammatically in the accompanying drawing, and, for the sake of clearness, only so much of a telegraphic equipment has been shown as will be necessary to a clear understanding 50 of the system.

In the drawing, Fig. 1 illustrates one embodiment of the present invention, while in

Figs. 2 and 3 there are shown respectively alternate arrangements for carrying out the features of the invention.

In describing this invention, attention will first be directed to Fig. 1 of the drawing, 60 in which the reference character L indicates a line conductor which terminates in a duplex equipment comprising ratio arms 1 and 2, each bridged by an associated condenser, an artificial line AL, transmitting 65 devices 3 and 4 and receiving devices as will presently be described. In tracing the effect of incoming message impulses which may be assumed as originating at a distant station (not shown) on the line L, a double pole 70 double throw switch 5 may first be considered as closed to its left-hand position, thereby permitting impulses from the line to become effective with a relay 6 which may be of polarized type and accordingly responsive 75 in step with the polarity changes of the incoming impulses. This arrangement corresponds with the common practice with regard to the reception of telegraphic impulses and in describing an alternate arrangement 80 for receiving impulses in a manner to permit the practising of the features of this invention, the switch 5 may be assumed as closed in its right-hand position. Impulses from the line L may now act through an electro- 85

magnet 10 to operate a microphone pile 11 which may be in the form of a telephone transmitter button. At this time a second double pole switch 13 will be understood as in its closed position, thereby permitting 90 variations of resistance in the microphone pile 11 to cause an associated battery 12 to effect current changes in the winding 16 of a transformer 15. In response to such currents in the winding 16 corresponding current changes are induced in the winding 18 95 of this transformer, and since the latter winding is connected to form a closed loop circuit which includes the winding of a moving coil 21 of a recorder 20 which may, 100 for convenience, be of the undulator type, these translated impulses will be thereby reproduced on a record strip 22 in the well-known manner. As well understood in connection with duplex working, messages may 105 be under transmission from the keys 3 and 4 during the time incoming message impulses are under reception as described, and since, as already pointed out, it is not possible to obtain, or at least maintain an absolute 110

balance between the real line L and the artificial line AL, some portion of the transmitted currents may traverse the circuits of the receiving devices. After passing 5 through the amplifier these extraneous currents may acquire a volume sufficient to interfere with the receiving device 20; therefore, in order to prevent this effect, a derived circuit extending from the neutral point of 10 the duplex equipment includes a switch 23, the winding 17 of the transformer 15 and an artificial line 24 to earth. By adjusting the capacity and resistance of the artificial line 24, it is possible to permit just sufficient 15 of the transmitted currents to pass through the transformer winding 17 as will neutralize any extraneous or stray portions of the transmitted currents which may reach the transformer winding 16 and prevent their 20 becoming effective with the transformer winding 18, thereby shielding the receiving device 20. It may be pointed out that the stray or surge effects from the transmitted currents which may become active in the 25 transformer winding 16, are, in general, in opposite phase or polarity relation with respect to such portions of the transmitted currents as may traverse the derived circuit through the transformer winding 17.

30 In the operations of securing a balance between the real line and the artificial line AL, the switch 23 may be moved to its open position, while the switch 5 may be moved to complete the circuit through the polar relay 6, and during the time the transmitting 35 keys 3 and 4 may be operated in respectively connecting the oppositely poled sources of line battery with the neutral point of the duplex equipment, adjustable devices (not 40 shown) included with the artificial line AL may be moved to vary the resistance, capacity and impedance of this artificial line to such point that the relay 6 will be unaffected by the currents controlled through the keys 45 3 and 4. The switch 23 may remain in its open position to disconnect the derived circuit, while the switch 5 may be moved to complete the receiving circuit to the amplifier control magnet 10. The switch 13 also 50 continues closed at this time. Operation of the transmitting keys 3 and 4 may continue while further adjustments of the artificial line devices may be carried out until the least indication of interference is produced by the undulator 20 on the record 22. The device 20 being more sensitive than the 55 relay 6, the last mentioned operations permit in general the closest possible adjustment between the circuits of the line L and the artificial line AL. At this time the switch 60 23 may be closed and while the transmitting keys 3 and 4 continue under operation the resistance and capacity of the second artificial line or network 24 may be varied until 65 the undulator 20 is not affected and may

produce a relatively straight line on the record 22. Due to the adjustments described, the duplex system will have been brought to the best condition of balance, following which messages may be transmitted 70 from the home station without affecting the receiving equipment at that point, while message currents from a distance station may be augmented by means of the current amplifier and thereafter rendered effective 75 with the receiving device 20 as already described.

Referring to Fig. 2 of the drawing, the arrangement shown therein differs from the one already described in that two windings 80 26 and 27 of a transformer 25 are connected to form the ratio arms of the duplex equipment, while the derived circuit which extends from the neutral point of this equipment is routed through a second winding 85 32 of a receiving device 30. In the reception of signaling impulses which may originate at a distance station, such currents in traversing the winding 26 of the transformer 25 induce corresponding currents in a 90 third winding 28 of this transformer. The switch 5 when positioned to connect the transformer winding 28 with the repeater control magnet 10 permits these currents to establish amplified current effects in a circuit 95 which includes the local battery 12 and one winding of a transformer 14; the switch 13, now in its left-hand position, connects a second winding of this transformer through a first winding 31 of the receiving device 100 30. The relation of the winding 32 being differential with respect to the winding 31 of the undulator 30, the network or artificial line 24 may be adjusted to such capacity and resistance values as will permit 105 only sufficient current from the operation of the transmitters 3 and 4 as will be necessary in the winding 32 for neutralizing the effect of surge or extraneous currents which may reach the winding 31 as a result of commercial or non-exact balance of the duplex 110 equipment of the line L and the artificial line AL. It may be pointed out that the windings 26 and 27 are connected to form a differential effect one winding with the 115 other with respect to currents transmitted from the keys 3 and 4; therefore such currents are neutralized in the transformer 25 and thereby rendered relatively non-effective with respect to the transformer winding 28.

For convenience of obtaining adjustments of balance in this duplex equipment, the switch 5 may be thrown to its left-hand position while the switch 13 may be thrown to 125 its right-hand position, thereby completing a closed loop circuit which includes the transformer winding 28 and the winding 31 of the undulator 30, the amplifier 10—11 being disconnected. The switch 23 may now be 130

opened to disconnect the derived equalizing circuit, while the keys 3 and 4 may be placed under operation and adjustments effected in the artificial line AL until the recorder 30 indicates the least activity and produces as nearly as possible the effect of a straight line on the record 22. The switch 23 may now be closed and while operations of the keys 3 and 4 continue, the electrical characteristics of the network 24 may be varied to such point that no effects are reproduced by the undulator 30. The switches 5 and 13 may now be moved to their right-hand and left-hand positions respectively, to establish the transformer winding 28 by way of the current amplifier 10-11 and the transformer 14 with the winding 31 of the recorder 30. Under this condition of the circuits, operation of the keys 3 and 4 may continue while further adjustments in varying the electrical characteristics of the network 24 may be carried out until such time as no movement effect may take place on the undulator 30. In this condition the adjustments of the duplex equipment will have been so placed that current impulses originating at the home station will be rendered non-effective on the receiving device, while incoming currents may be augmented through the amplifier and reproduced by the receiving device 30, as described.

The alternate embodiment of this invention, as shown in Fig. 3 of the drawing, differs from the arrangement shown in Fig. 2 in that current amplifiers of the well-known thermionic type have been substituted for the microphonic current amplifier already described. For convenience, this repeater has been arranged in accordance with the so-called "two-step" plan. The first repeater 40 comprises a thermionic cathode or filament 41 which is heated by current from a source 42, an input electrode or grid 43 and an output electrode or plate 44. The output electrode 44 is maintained positive with respect to the filament 41 by means of a source of direct current. In arrangements of this type, it is preferable to place an impedance 46 in series with the direct current source and to connect the true output circuit in parallel with the battery and impedance. Such output circuit usually contains a condenser 47 so that this circuit is affected only by changes in the output current.

It is well understood in connection with vacuum tube devices of this type that any change in potential difference between the electrodes 43 and 41 will cause a corresponding change in current in the output circuit. In describing the second-step circuit, thermionic repeater 50 is provided with a filament 51 which is also heated by means of the battery 42, an input grid 53 and an output plate 54. The input circuit of the repeater 50, includes a battery 55, the grid 53,

the filament 51 and an impedance unit 52. The output or work circuit of the repeater 50 is connected to the terminals of a switch 13 and has bridged across it a battery supply circuit, including the battery 45 and the impedance 56, for maintaining the plate 54 positive with respect to the cathode 51. By means of switch 13 this output circuit may be connected to the winding 31 of the undulator 30. It will be clear that during the time the switches 5 and 13 are in their right-hand and left-hand positions respectively, incoming impulses from the line L as manifested through the transformer winding 28 will cause variations in the potential difference between the grid 43 and filament 41 of the repeater 40. As commonly understood this variation of potential in the input circuit will cause a variation corresponding in kind but of increased amplitude, in the potential differences between the grid 53 and cathode 51 of the repeater 50, and will result in an output current through the winding 31 which will have the wave form of the original received current but the amplitude of which will be sufficiently greater to cause effective operation of the undulator 30.

In arriving at a first or preliminary adjustment balance of the duplex equipments, the switches 5 and 13 may be placed in their left-hand and right-hand positions respectively, thereby disconnecting amplifiers 40 and 50 and connecting the transformer winding 28 in a closed loop circuit through the winding 31 of the recorder. At this time the switch 23 should also be positioned to disconnect the derived circuit through the differential winding 32 of the receiving device 30. Adjustments of the artificial line devices may now be carried out in a manner similar to that already described in connection with Fig. 2 of the drawing, following which the switches 5 and 13 may be moved to their opposite positions to connect the amplifiers 40 and 50 intermediate the transformer winding 28 and the undulator 30, following which further adjusting operations may be proceeded with as also described in connection with the arrangement shown in Fig. 2.

Although the thermionic type of amplifier has been illustrated in connection with the duplex equipment shown in the last two figures of the drawing, it will be understood that this amplifier arrangement may be substituted for the microphonic amplifier system shown in connection with the bridge duplex arrangement illustrated in Fig. 1 of the drawing and that in fact any suitable type of amplifier may be used with either arrangement. It will be pointed out that instead of employing the double or two-step amplifying arrangement shown in Fig. 3, that either a single or a multiple step arrangement may be employed in which one only or several amplifiers similar to the

amplifiers 40 and 50 may be respectively employed.

Although the embodiments chosen for illustrating the features of this invention are considered to represent preferred arrangements, it will be understood that changes in the organization of the apparatus may be made without departing from the spirit of this invention.

10. What is claimed is:

1. In a telegraph system, the combination of a duplex set comprising a pair of ratio arms, an artificial line, direct current transmitting means connected with the apex of 15 said ratio arms, a transformer having a primary coil, means for connecting said primary coil in bridge of said ratio arms, an alternating current receiving device associated with the secondary coil of said transformer, a leak circuit also connected with the apex of said ratio arms and including a third coil of said transformer for rendering said receiving device non-responsive to the 20 operation of said direct current transmitting means.

2. In a telegraph system, the combination of a duplex set comprising a pair of ratio arms, an artificial line, direct current transmitting means connected with the apex of 30 said ratio arms, a transformer having a primary winding, means for connecting said primary winding in bridge of said ratio arms, an alternating current receiving device associated with the secondary winding 35 of said transformer, a leak circuit also connected with the apex of said ratio arms and including a third winding of said transformer for rendering said receiving device non-responsive to the operation of said 40 transmitting means, and means connected in said leak circuit whereby the current flow therein may be varied.

3. A telegraph system comprising a line conductor, a pair of ratio arms connected to 45 said conductor, direct current transmitting means connected to the apex of said ratio

arms, a transformer having a primary winding, means for connecting said primary winding in bridge of said ratio arms, an alternating current receiving device connected with the secondary winding of said transformer, a leak circuit also connected to the apex of said ratio arms, and means included in said leak circuit and associated with said transformer, whereby said receiving device 55 is rendered non-responsive to the operation of said direct current transmitting means.

4. A telegraph system comprising a line conductor, a pair of ratio arms connected to said conductor, direct current transmitting 60 means connected with the apex of said ratio arms, a transformer having a primary coil, means for connecting said primary coil in bridge of said ratio arms, an alternating current receiving device connected with the secondary coil of said transformer, an amplifier interposed between said transformer and ratio arms, a leak circuit also connected to the apex of said ratio arms, and means included in said leak circuit and forming a 65 part of said transformer for rendering said receiving device non-responsive to the operation of said direct current transmitting means.

5. In a telegraph system, the combination 75 of a duplex set comprising a pair of ratio arms, an artificial line, direct current transmitting means connected with the apex of said ratio arms, a transformer having a plurality of windings, an alternating current 80 receiving device associated with the windings of said transformer, a leak circuit directly and conductively connected with the apex of said ratio arms, and including a 85 winding of said transformer for rendering said receiving device non-responsive to the operation of the direct current transmitting means.

In witness whereof, I hereunto subscribe my name this 23rd day of May, A. D. 1918.

GEORGE C. CUMMINGS.
